(57) **CLAIM**

The ornamental design for a non-curved rim of fan, as shown and described.

DESCRIPTION

FIG. 1 is a perspective view of a non-curved rim of fan showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a sectioned right side view thereof;

FIG. 9 is perspective view showing the non-curve rim installed on a fan; and,

FIG. 10 is a front perspective view showing the fan components exploded.

The broken line showing of the fan is included for the purpose of illustrating use and environment and forms no part of the claimed design.
